(57) **CLAIM**

The ornamental design for a vehicle hood, as shown and described.

DESCRIPTION

FIG. 1 is a rear right upper perspective view of a vehicle hood, showing my new design;

FIG. 2 is a right side elevational view thereof, the left side being a mirror image;

FIG. 3 is a rear elevational view thereof;

FIG. 4 is a front elevational view thereof;

FIG. 5 is a top plan view thereof; and,

FIG. 6 is a bottom plan view thereof.

The dash-dot even broken lines illustrate and surround portions of the vehicle hood that form no part of the claimed design.

1 Claim, 4 Drawing Sheets
